UNITED STATES PATENT OFFICE.

WILLIAM A. LORENZ AND WILLIAM H. HONISS, OF HARTFORD, CONNECTICUT, ASSIGNORS TO FELIX W. LEINBACH AND CLARENCE A. WOLLE, OF BETHLEHEM, PENNSYLVANIA.

PAPER-BAG MACHINE.

SPECIFICATION forming part of Letters Patent No. 337,966, dated March 16, 1886.

Application filed June 20, 1885. Serial No. 169,275. (No model.)

To all whom it may concern:

Be it known that we, WILLIAM A. LORENZ and WILLIAM H. HONISS, both of Hartford, Connecticut, have invented certain new and useful Improvements in Paper-Bag Machines, of which the following description and claims constitute the specification, and which are illustrated by the accompanying four sheets of drawings.

10. This machine manufactures continuous tucked paper tubing into paper-bag blanks, which have one end folded down into the diamond shape shown in Figure 4 of the drawings, and which may be manufactured into paper bags by means of machinery shown in our application of May 15, 1884, for Letters Patent of the United States. The diamond-folding mechanism of this machine is similar in many respects to that shown in our application of 15 February 24, 1885, for Letters Patent of the United States for a machine to perform the same function, but in other respects it is substantially different from that and from every other mechanism known to us.

20. Fig. 1 of the drawings is a plan view of a section of tucked paper tubing of suitable length for a bag-blank, and Fig. 2 is an end view of the same. Fig. 3 is a plan view of the tube of Figs. 1 and 2 after one end thereof has been folded down into the desired diamond shape, but before the folding mechanism has been withdrawn therefrom. Fig. 4 is a plan view of the same after such withdrawal. Fig. 5 is a side view of this machine. Fig. 6 is a plan view of what is shown in Fig. 5, but with the oscillating presser-plate broken away on the line *c d* in order to show the parts below the same. Fig. 7 is a sectional view looking to the left from the line *a b* of Fig. 6. Fig. 8 is a side view of parts of the diamond-folding mechanism when partly turned over in doing its work. Fig. 9 is a side view of the same when fully turned over and in the position relative to the blank which is shown in Fig. 4. 30 Fig. 10 is a plan view of the broken-away oscillating presser-plate and of its appurtenances.

The stud 1 has a bearing for the loose pulley 2 and another for the hub of the working-

50 pulley 3. Both pulleys are driven in the direction indicated by the arrow adjacent to the belt shown in Fig. 5.

The numerals 4 and 5 indicate the upright sides of the frame of the machine. The gear 6 is fixed to the hub of the pulley 3 and meshes with the gear 7 on the shaft 9, while the gear 7 meshes with the gear 8 on the shaft 10. The shafts 9 and 10 carry the drawing-rolls 11 and 12, which rolls draw the tucked paper tubing into the machine from an adjacent machine 60 adapted to manufacture the same. The extremity of the tube-former of such a machine is shown in Figs. 5 and 6, and is indicated by the numeral 13. The tucked paper tube 14 has the tucks 15 and 16, the lower folds, 65 17 and 18, the upper folds, 19 and 20, and the seam 21. The cutting-rolls 24 and 25 are keyed to the shafts 26 and 27, respectively, and receive motion from the gear 6, meshing with the gear 28 on the shaft 26, while the gear 28 meshes with the gear 29 on the shaft 27. The upper drawing-roll, 12, and the upper cutting-roll, 25, are subjected to the downward pressure of the springs 30 and 31, respectively, which springs bear downward upon the sliding boxes 32 and 33, respectively, and are adjustable by the thumb-screws 22 and 23, respectively. Similar springs, boxes, and thumb-screws are also used on the other side of the machine to press downward upon the other 70 ends of the upper drawing-roll and cutting-roll. The knife 34 is fixed in the periphery of the cutting-roll 25, and lengthwise thereof, while the rubber pad 35 is fixed correspondingly in the periphery of the cutting-roll 24. 75 80 85

The drawing-rolls have annular recesses on their peripheries, and the cutting-rolls have corresponding recesses extending part way around their peripheries, as shown in Fig. 6. The object of these recesses is to give room for the passage of the six turns in the tucked paper tubing without flattening them down, and thus depriving them of their elasticity.

A reciprocating carriage, 38, slides on ways 39 and 40, supported by brackets 41 and 42. 90 The carriage is driven by the crank 43 through the crank-pin 44, the connecting-rod 45, and the carriage-pin 46. The lower presser-plate, 47,

is attached to the carriage by the pivot 48, near its rear end, while its forward end is supported by the arm 49. The lower end of that arm is provided with the roller 50, and that roller runs forward and backward in the groove 51, passing over the trip-cam 52 in its forward movement and under that cam during its backward motion. The cam is hinged by the pivot 53 to the inner surface of the groove, so that it may oscillate on a vertical plane parallel with that surface. The shaft 54 oscillates in brackets which project forward and downward from the forward end of the lower presser-plate, 47. The bevel-gears 55 and 56 are keyed to that shaft, and mesh with the bevel-gears 57 and 58, respectively, which are respectively keyed to the shafts 59 and 60, and which shafts turn in brackets projecting downward from the lower side borders of the lower presser-plate, 47. The shafts 59 and 60 carry the lower side grippers, 61 and 62, respectively, while the shaft 54 carries the lower front grippers, 63. All these three shafts are oscillated in unison by the crank 64. That crank is provided with the roller 65, projecting horizontally from its outer end, and running upon the level rail 66. The upper and oscillating presser-plate, 67, is attached to the carriage by the pivot 68 at its rear edge, and is made to oscillate by the gear 69, the sector-gear 70, the connecting-rod 71, the slide 72, the roller 73, and the cam 74, which cam is fixed to the crank-pin 44. The range of oscillation of the upper presser-plate is from the position shown in Fig. 5 to that shown in Fig. 9. The shaft 75 oscillates in brackets projecting forward and upward from the forward edge of the upper and oscillating presser-plate, 67. The bevel-gears 76 and 77 are keyed to that shaft and mesh with the bevel-gears 78 and 79, respectively, which gears are respectively keyed to the shafts 80 and 81, and which shafts turn in brackets projecting upward from the upper side borders of the upper presser-plate, 67. The shafts 80 and 81 carry the upper side grippers, 82 and 83, respectively, while the shaft 75 carries the upper front gripper, 84. All three of these shafts are oscillated in unison by the arms 85 and 86, alternately. The arm 85 is provided with the roller 87, projecting horizontally from its outer end and striking upon the rail 88. The arm 86 is provided with the roller 89, striking upon the rail 90. The springs 91 and 92 act upon the grippers 63 and 84, respectively, and through them and the lower and upper shafts and bevel-gears, respectively, upon the lower and upper side grippers, in such a way as to keep all the grippers closed upon their respective presser-plates, except when such action is prevented by the roller 65 colliding with the rail 66, or by the roller 87 colliding with the rail 88, or by the roller 89 colliding with the rail 90, as the case may be. The platform 93 supports the paper tubing while it passes from the cutting-rolls to the presser-plates.

The mode of operation is as follows: The tucked paper tubing is continuously drawn into the machine by the drawing-rolls 11 and 12, and is projected into the space which is between the rear edge of the upper presser-plate, 67, and the upper side of the lower presser-plate, 47, when the roller 50 rests upon the lower side of the groove 51, and is projected still farther forward till its forward end reaches the forward borders of the two presser-plates. Shortly before that moment of time the carriage 38 begins its forward movement, and that movement forces the roller 50 to mount upward along the left-hand inclined end of the cam 52 to the position shown in Fig. 5, and also releases the roller 65 from downward pressure upon the rail 66. That forcing upward of the roller 50 raises the presser-plate 47 to the position indicated in Fig. 5, and thus clasps the paper tubing between its upper side and the rear edge of the upper presser-plate, and that releasing of the roller 65 allows the spring 91 to oscillate the shaft 54, and by so doing to force the gripper 63 to clasp the forward end of the lower ply of the paper tubing down upon the forward border of the lower presser-plate, and also to force the grippers 61 and 62 to clasp the lower folds of the paper tubing down upon the side borders of that presser-plate. When the forward end of the paper tubing reaches the forward borders of the two presser-plates, the sector 70 begins its forward movement, and thus raises the upper presser-plate upon its pivot, and also raises the roller 87 from the rail 88, and thus allows the spring 92 to oscillate the shaft 75, and by so doing to force the gripper 84 to clasp the forward end of the upper ply of the tucked paper tubing up against the forward border of the upper presser-plate, and to force the grippers 82 and 83 to clasp the upper folds, 19 and 20, respectively, up against the respective side borders of that presser-plate. Then the knife 34 severs a bag-length from the paper tubing, and as the carriage 38 and sector 70 proceed still farther on their forward movement the upper presser-plate continues to oscillate upon its pivot from the position shown in Fig. 5, through that shown in Fig. 8, nearly to that shown in Fig. 9. Thus the grippers 82, 83, and 84 act against the grippers 61, 62, and 63 to open out the end of the bag-length of Figs. 1 and 2 into the diamond form of Fig. 3. Then the roller 50 passes off from the right-hand end of the cam 52 to the bottom of the groove 51, and in so doing depresses the lower presser-plate, so that it no longer clasps the bag-blank between it and the pivoted edge of the upper presser-plate, and also forces the roller 65 hard down upon the rail 66, thus lifting the grippers 61, 62, and 63 against the action of the spring 91 from pressing down upon the bag-blank. At the same time the roller 89 collides with the rail 90, and thus lifts the grippers 82, 83, and 84 against the resistance of the spring 92 from pressing any

longer those places in the bag-blank which they have clasped upon the borders of the presser-plate 67. Thus released from all the grippers and from being clasped between the 5 two presser-plates, the bag-blank may be withdrawn from the machine by any proper mechanism, which may also transfer it to other machinery for making the subsequent folds of the bottom of the bag. Then the carriage 38 and 10 the sector 70 make their backward motions, the roller 50 passing under the cam 52, and thus holding the lower presser-plate away from the pivoted edge of the upper presser-plate, in order to give abundant entrance to the new end of 15 the tucked paper tubing, and also holding all the lower grippers open by means of the collision of the roller 65 with the rail 66, and the roller 87 colliding at the end of the movement with the rail 88, and thus opening all the upper 20 grippers for the reception of the upper ply and upper folds of the bag-blank next to be operated upon.

We do not herein claim the combination of the carriage 38, a presser-plate pressing downward upon the carriage, two grippers pressing downward upon the side borders of the upper 25 surface of the carriage, and two pairs of grippers oscillating in an arc of a circle above the

carriage, that combination being covered by claim 4 of our application No. 156,865 for Letters Patent of the United States of America, filed February 24, 1885. 30

We claim as our invention—

1. The combination of the side grippers, 61 and 62, the front gripper, 63, the shafts 54, 59, 35 and 60, the bevel-gears 55, 56, 57, and 58, the arm 64, the rail 66, and the spring 91, all substantially as described.

2. The combination of the presser-plate 47, oscillating on the pivot 48, and the presser-plate 40 40 67, oscillating on the pivot 68, substantially as described.

3. The combination of the presser-plate 47, provided with the grippers 61, 62, and 63, with the presser-plate 67, provided with the grippers 45 82, 83, and 84, substantially as described.

4. The combination of a presser-plate, oscillating on a pivot, and two side grippers and one front gripper clasping a paper tube to that presser-plate, all substantially as described.

WILLIAM A. LORENZ.

WILLIAM H. HONISS.
